UNITED STATES PATENT OFFICE.

OLAUS JENSEN, OF SEATTLE, WASHINGTON, ASSIGNOR OF ONE-HALF TO OLSWANG BROS. & CO., OF SEATTLE, WASHINGTON.

SHOEMAKER'S JACK.

1,138,383.

Specification of Letters Patent.

Patented May 4, 1915.

Application filed August 27, 1914. Serial No. 858,883.

To all whom it may concern:

Be it known that I, OLAUS JENSEN, a citizen of the United States, residing at Seattle, in the county of King and State of Washington, have invented certain new and useful Improvements in Shoemakers' Jacks, of which the following is a specification.

This invention relates to shoemakers' jacks; and its object is the improvement in 10 such devices to render the same more convenient and efficient to operate.

With these ends in view the invention consists in the novel construction and adaptation of parts as will be hereinafter described 15 and claimed.

In the accompanying drawing, Figure 1 is a side elevation of a shoemaker's jack embodying my improvements. Fig. 2 is a front elevation of the same with the last-toe support omitted. Fig. 3 is a vertical longitudinal section of the upper portion of the standard with the last-support in elevation. Fig. 4 is a perspective view of the last-toe support shown detached.

According to this invention I provide a standard comprising an upper member 5, a base member 6 and an intermediate member 7, which is employed only when the operator works in a standing position. Said 25 members are separably and rotatably connected by means of tenon elements such as 8 (Fig. 3) formed at the lower ends of the members 5 and 7 to fit into sockets, as 9, provided in the upper ends of the intermediate and base members.

10 represents a post having its upper end, as at 10¹, adapted to fit within a recess therefore in a last 11. The post is furthermore provided at about its midlength with a 40 spherical portion 12 adapted to seat in a cup bearing formed in the enlarged upper end 13 of the member 5 of the standard. Below its spherical part, said post is provided with a cylindrical stub 14 which is 45 adapted to engage in a socket 15 provided in the member 5 for securing the post in an upright position, or the post may be held in a substantially horizontal position, as indicated by broken lines A in Fig. 1, by having 50 its stub engage under a wicket shaped lug 13¹ provided on said upper member, while a saddle 13² provided in the latter supports the post at the other side of the spherical part thereof. Hinged by a pin 17 to lugs 18, 55 which extend upwardly from a floor plate 6¹

formed integral with said base member, is a U-shaped pedal formed of side elements 19 and an end element 19¹.

20 represents a strap for holding shoes or the like on the last. Said strap has its ends 60 connected by helical springs 21 with the respective side elements 19 of the pedal.

22 is an arm pivotally connected at its upper end to ears 23 on the base by a pin 24. Said arm is provided with serrations or 65 teeth 25 which are utilized to engage the element 19¹ of the pedal for holding the latter at selected heights in opposition to springs 26 and afford the requisite tension upon the strap through the medium of the 70 springs 21. Another spring 27 is utilized to yieldingly push the free end of the arm 22 outwardly from the standard into position to be engaged by the pedal. The lower end of said arm is provided with an outwardly 75 extending finger 22¹ to be encountered by the operator's foot for convenience in pushing said arm from its engagement with the pedal when the strap is to be released from the work on the last. Said strap is led 80 through guides 28 disposed at opposite sides of the head part 13 and whereby the effective length of the strap is not materially changed with the last supporting post in either its upright or inclined positions.

85 In the manufacture of new shoes I provide a device for supporting the toe of a last, such device consists of a bar 29 arranged to be detachably connected to the standard by the provision of spaced collars 30 and 31 on 90 the bar engaging over the standard, and having the lower collar 31 rest on a flange 32 provided on the standard. The upper end of the bar is provided with a concave plate 33 which serves as a stirrup for a last 95 toe.

In operation, the post 10 may be used as before explained in either an upright position as shown by full lines in Fig. 1 or in a substantially horizontal position as indicated by broken lines A in the view. To either of such positions the springs 21 accommodate themselves without adjusting the regulating treadle therefor.

100 By passing the belt through the guides 28 the effective lengths of the strap for the above mentioned positions of the post is varied to but a small extent with no appreciable variation to the strain exercised by 105 springs 21 upon the belt.

The last may not only be swung with the post in a vertical plane but may also be turned by rotating the post with respect to the axis of the stub 14. To both of such movements it is obvious that the ball-and-socket connection afforded by the postpart 12 in the head 13 accommodates itself.

What I claim, is:—

1. In a jack, the combination with the standard provided with strap guides and a socket in its upper end, of a last supporting post having a spherical central portion adapted to seat in said socket, the portion of the post below said spherical portion forming a stub adapted to engage the standard to secure the post in substantially upright and horizontal positions, a pedal attached to the lower portion of said standard, a strap extending through said guides, springs connecting the ends of the strap with said pedal, and spring pressed means for securing the pedal in adjusted positions.

2. In a jack, the combination with a standard, a post adjustably secured thereto for rotary and oscillatory movements, a last detachably connected to said post, a strap and adjustable means connected with said standard for regulating the tension of the strap, of a toe support for the last, said toe support comprising a bar revolvably connected to said standard and terminating at its upper end in a concave head.

3. In a jack, the combination of a standard formed of a plurality of interfitting parts, a post formed to make a ball-and-socket connection with the uppermost of the standard parts, means for securing said post in positions substantially in axial alinement and in rectangular relations with respect to the standard, a last adapted to be detachably

secured to said post, a strap, adjustable means for regulating the tension of the strap when applied to the last and a toe support for the last comprising a bar removably mounted on said standard and terminating at its upper end in a head adapted to receive the toe of the last.

4. In a jack, the combination with the standard provided with strap guides and a socket in its upper end, of a last-supporting post having a spherical central portion adapted to seat in said socket, the portion of the post below said spherical portion forming a stub adapted to engage the standard to secure the post in substantially upright and horizontal positions, a pedal attached to the lower portion of said standard, a strap extending through said guides and connected to said pedal, and means for securing the pedal in adjusted positions.

5. In a jack, the combination with a standard, of a post formed to make a ball-and-socket connection with said standard, strap guides positioned at opposite sides of the standard and in proximity of the axis of said ball-and-socket connection, means for maintaining said post in positions substantially in axial alinement or in rectangular relations with respect to the standard, a last for the post, a strap passing through said guides, and adjustable means provided on the standard for regulating the tension of the strap.

Signed at Seattle, Washington, this 4th day of August, 1914.

OLAUS JENSEN.
